Application October 10, 1940, Serial No. 360,549

18 Claims. (Cl. 264—14)

This invention relates to hydraulic governing mechanism for controlling the admission of motive fluid to prime movers and it has for an object to provide apparatus of this character wherein in the regulating or controlling pressure, in addition to controlling the position of the servo-motor pilot valve, also serves to secure operation of the operating piston without the latter operation introducing fluctuations in the impeller pressure sufficient to impair the speed responsive effect of the latter.

Heretofore, impellers developing liquid pressure and varying substantially as the square of the prime mover speed have been used to provide a controlling or regulating pressure for the servo-motor operating the motive fluid admission valve. Ordinarily such controlling or regulating pressure is used to control the position of the servo-motor pilot valve and the operating piston is moved by a separate source of motive fluid, movement of the operating piston by liquid under pressure developed by the impeller being objectionable on account of pressure fluctuations being produced thereby. In accordance with the present invention, movement of the operating piston is secured by the application of fluid pressure derived from the impeller without introducing such fluctuations or pulsations, this result being effected by the use of a constant-flow valve in the line supplying liquid from the impeller to the operating piston, the operating piston and its cylinder incorporating an accumulator providing, at least, for admission valve closing movements which do not depend upon the rate at which liquid is supplied to the operating cylinder.

A further object of the invention is to provide servo-motor apparatus of the above character wherein the fluid draining therefrom is supplied to the impeller so as to improve the suction lift of the latter.

A further object of the invention is to provide apparatus of the above character wherein the liquid used is lubricating oil and drainage from the operating cylinder is provided at a sufficient pressure for bearing lubrication.

These and other objects are effected by the invention as will be apparent from the following description and claims taken in connection with the accompanying drawings, forming a part of this application, in which:

Fig. 1 is a diagrammatic and sectional view showing one form of the improved apparatus;

Fig. 2 is a view similar to Fig. 1 but showing a second embodiment;

Fig. 3 shows a third embodiment similar in many respects to that of Fig. 2; and,

Fig. 4 shows a fourth embodiment.

Referring to Fig. 1, there is shown a centrifugal impeller, at 10, driven from the prime mover or turbine, at 11, and furnishing controlling and motivating liquid for the servo-motor, at 12, which operates the admission valve 13. An important feature of the present invention is to provide for operation of the servo-motor by motive liquid supplied by the impeller without impairing the efficacy of the impeller pressure to exert a pulsation-free speed-responsive controlling effect on the servo-motor.

The impeller, at 10, is of the type commonly used for governing purposes and it comprises a runner 14 and a casing 15. The casing provides a pressure space 16 bounding the runner and a suction space 17 at one end of the latter, the casing having an eye 18 axially aligned with the runner and opening into the suction space.

A suction conduit 19 provides for passage of liquid from the reservoir 20 through the eye to the suction space. Preferably, as is common practice with hydraulic governing apparatus, the inlet end of the suction conduit 19 is formed with a mixing or combining cone or chamber 21 into which liquid furnished from the chamber 16 is discharged at high velocity from the jet 22.

The servo-motor, at 12, comprises suitable housing structure 23 providing the operating cylinder and pilot valve bores 24 and 25 within which are disposed the operating piston 26 and the pilot valve 27, respectively.

The operating piston 26 is connected by a linkage, at 28, to the admission valve 13, and by a follow-up linkage, at 30, to the pilot valve 27. The linkage, at 28, may comprise an operating piston rod 32, a link 33, a lever 34, and a valve rod 35 pivotally connected together and the lever having a fulcrum 36; and the linkage, at 30, may include the piston rod 32, the link 33, a fulcrumed lever 37, a link 38, and a compression spring 39 engaging the piston valve 27.

The structure 23 has passages 40 and 41 communicating with the operating cylinder bore 24 at either side of the operating piston 26 and communicating with the pilot valve bore through suitably located ports 42 and 43. The pilot valve 27 has spaced enlargements 44 and 45 defining, with the bore 25, a connecting space or chamber 46 for the ports 42 and 43, and the enlargement 44 being arranged to cover more or less the port 42.

The pilot valve 27 has a piston face 47 at its lower end cooperating with the closed lower end of the pilot valve bore 25 to form the pressure chamber 48 connected by a conduit 49 to the impeller pressure space 16. Also, the upper end of the pilot valve bore 25 is preferably connected by a drain conduit 51 to the reservoir 20.

The operating piston 26 divides the operating cylinder bore 24 into an expansible and contractible chamber or space 52 thereabove and a drain chamber or space 53 therebelow and forming a part of the drain space, the passages 40 and 41 communicating, respectively, with the chambers 52 and 53. The drain chamber 53 is connected to the drain conduit 54, also forming a part of the drain space and the operation of which will be more fully hereinafter set forth.

The constant flow valve, at 56, supplies liquid to the expansible and contractible chamber 52 without changes of rate of flow and consequently does not cause any fluctuations in the impeller pressure with undesirable effects on the speed-controlling relay.

The constant flow valve, at 56, makes use of the principle of two orifices in series, the first of which is fixed and the second of which is varied in response to change in pressure at the downstream side thereof, to maintain substantially constant flow irrespective of what the downstream pressure may be at the discharge side of the second or variable orifice. As shown, the valve includes a cylinder 58 connected to the conduit 55 and having one or more lantern openings or ports 59 communicating with the space 60 at the downstream side of the second or variable orifices and communicating with the expansible and contractible chamber 52. A tubular member 61 is slidably in the enlargement, the forward portion thereof being formed to provide the fixed orifice 62 and the rearward end portion 63 thereof functioning as a slide valve to cover the opening or openings 59 to a variable extent in order to provide the second or variable orifice. A spring 64 exerts its force on the tubular member in a direction tending to uncover the lantern opening or openings 59 and thereby to increase the flow area of the second orifice, the force of the spring being opposed by that of the differential of liquid pressure across the fixed orifice 62 and acting on the annular piston area provided by the forward end of the tubular member 61. The spring force is varied by adjustment of the follower 65. If the pressure at the downstream side of the second or variable orifice should change, this would induce a pressure change in the space between the orifices, thereby upsetting the differential across the first orifice, and the tubular member would move in such a direction as to give a compensating effect so as to maintain flow through the two orifices substantially constant, irrespective of pressure variations at the downstream side of the second or variable orifice.

With the expansible and contractible chamber 52 of the operating cylinder supplied with liquid from the impeller through the conduit 55 and its constant flow valve, at 56, it will be apparent that, with suitable operation of the pilot valve 27, the capacity exists for providing the necessary change in pressure in the expansible and contractible chamber 52 to provide for proper valve operation. Normally, for a given load, the piston 26 would occupy an equilibrium position with the force of fluid pressure acting thereabove in equilibrium with the force of the spring

means 57 acting therebelow, and the pilot valve 27 would occupy a position with the fluid and spring forces acting thereon in equilibrium, the portion 44 of the pilot valve covering the port 42 sufficiently to maintain the required pressure in the chamber 52 such that the outflow of liquid therefrom through the passage 40 will be equal to the inflow of liquid thereto which is constant from the passage 55. If the load should decrease, the speed and impeller pressure would increase, thereby upsetting the equilibrium condition of the pilot valve 27 and causing the latter to move upwardly, decreasing the restriction of the port 42 to provide for the same rate of discharge with a reduced pressure in the expansible and contractible chamber 52, the reduced pressure therein permits the then preponderating force of the spring means 57 to cause the operating piston 26 to move the motive fluid admission valve member 13 in a closing direction. In addition to the increased force of compression of the spring 39 brought about by upward movement of the pilot valve 27 in response to increase in impeller pressure, the force of compression of the spring would further be increased concurrently with movement of the operating piston due to operation of the follow-up linkage, at 38, and movement of the operating piston 26 would continue until the equilibrium condition is again restored with the opening of the admission valve restricted suitably for the decrease in load.

If the load should increase, both the speed and impeller pressure would decrease, thereby upsetting the equilibrium of forces acting on the pilot valve 27, the preponderating spring force moving the latter downwardly to further restrict the port 42, in consequence of which the pressure would build up in the expansible and contractible chamber 52 and the operating piston would, on that account, be moved against the spring 57 to move the valve member 13 in an opening direction. These operations would continue until an equilibrium condition is attained with the admission valve adjusted to proportion the motive fluid pressure suitably for the increase in load.

The drain conduit 54, forming part of the drain space, is preferably arranged to improve the suction effect of the impeller. Accordingly, it is formed so that its discharge end 66 is axially aligned with the impeller and the eye for discharge into the latter.

Furthermore, where the liquid is lubricating oil, the drain conduit may be modified to provide a pressure source for bearing lubrication, in which event, as shown in Fig. 1, the drain conduit 54 would have first and second branches 67 and 68, the branch 67 having a spring loaded relief valve 69 and the discharge end 66 and the branch 68 leading to the bearings having a constant flow valve, at 70, similar to that already described. The spring loaded relief valve operates to maintain a desired pressure at the upstream side thereof and ahead of the constant flow valve, at 70, and the latter operates to provide for constant flow with the maintenance of substantially constant pressure upstream thereof, irrespective of variations in pressure at the downstream side thereof.

In Fig. 2, the expansible chamber or space, instead of being provided entirely within the operating cylinder bore, as in Fig. 1, is provided partly therein, as shown at 52a, and partly, as shown at 52b, in a separate structure, at 72. In this view, the operating cylinder bore is divided into

the expandable and contractible space or chamber 52a and the drain space or chamber 53a, and passages 40a and 41a join such spaces with the interior of the piston valve bore 25a, the piston valve 27a having a piston enlargement 44a cooperating with the port end 42a of the passage 40a.

The pilot valve has an upper enlargement 45a, which, with the enlargement 44a and in cooperation with the bore 25a, provide a space for connecting the ports 42a and 43a so that liquid may be transferred from the chamber 52a to the chamber 53a. In addition, the pilot valve 27a has a lower enlargement 73, which, with the central enlargement 44a cooperate with the bore 25a to provide a space 74 which communicates with the port 42a, in the event of sufficient upward movement of the pilot valve 27a.

The means for supplying motive liquid to the chamber 52a, instead of communicating directly and continuously therewith, as in Fig. 1, supplies such liquid through a conduit 55a, the constant flow valve at 56a, to the chamber 52b, and, from the latter, liquid is conducted by the conduit 55b to the space 74.

The structure, at 72, provides a bore 76 within which is disposed a piston 77, the latter dividing the bore into the expandable chamber 52b and the drain chamber 53b. A spring 78 in the chamber 53b exerts force on the piston 77 in opposition to the force of fluid pressure applied thereto. The piston 77 has an opening 79 with which cooperates the plug 80 depending from and adjustably carried by the top 81 of the structure, at 72, the plug having a lower tapered end 82 so that downward movement of the piston may be limited, the piston moving downwardly until the escape of liquid through the opening 79 is equal to that supplied to the chamber 52b by the constant flow valve, at 56a. By adjusting the plug 80, the maximum volume of the chamber 52b may be varied, its capacity preferably being at least about three-quarters of that of the operating cylinder.

In Fig. 2, impeller pressure is supplied to the upper end of the pilot valve bore 25a by the conduit 48a, the drain conduit 51a being connected to the lower end of the bore.

Comparing Figs. 1 and 2, it will be seen that the operations of transferring liquid from the contractible and expandable spaces or chambers 52 and 52a to the drain spaces or chambers 53 and 53a to secure rapid contraction of the contractible and expandable chambers are the same. On the other hand, the expanding movements of these chambers are different. In Fig. 1, the rate at which the chamber 52 is expanded depends upon the rate of inflow and the extent of escape. In Fig. 2, opening of the admission valve is much more rapid for the reason that the supply of liquid accumulated in the chamber 52b is available for transfer to the space 52a to secure rapid expansion of the latter with downward movement thereof and movement of the admission valve in an opening direction when the conduit 55b is placed in communication with the port 42a by the piston valve space 74.

Fig. 3 is similar to Fig. 2 except that the drain passage 54a is modified to provide for bearing lubrication, as hereinbefore described in connection with Fig. 1.

Fig. 4 is fundamentally similar to Fig. 2 in that accumulator and liquid transfer features provide for rapid opening and closing move-

ments of the admission valve independently of the rate at which motive liquid is supplied from the impeller. In this view, the accumulator features are provided in the operating cylinder.

5. The operating cylinder bore 24b of Fig. 4 is divided by the pistons 26b and 71a into expandable and contractible chambers 52c and 52d and the drain chamber 53c.

The piston 71a has an opening 79a with which cooperates a plug 80a carried by the upper piston 26b. The spring means 57a is arranged between the pistons 26b and 71a and a spring 84 bears against the upper face of the piston 26b.

The impeller pressure conduit 55c has a constant flow valve, at 56b, discharging into the chamber 52d and the latter is connected, by the passage 55d, to the piston valve space 74a, the piston valve construction being similar to that of Fig. 2, that is, with increase in impeller pressure due to decrease in load, the piston valve space 46b places the passages 40b and 41b in communication so that liquid may discharge from the chamber 52c into the chamber 53c, and, upon upward movement of the piston valve, in consequence of increase in load, the piston valve space 74a places the passage 55d in communication with the passage 40b to supply liquid from the accumulator space or chamber 52d to the chamber 52c.

30. In order that the operation of the construction shown in Fig. 4 may be better understood, consideration should be given to the forces acting on the composite piston arrangement constituted by the pistons 26b and 71a. Normally, the pistons would occupy an equilibrium position, the force of fluid pressure and the force of the spring 84 acting downwardly on the piston 26b being balanced by the upwardly-acting spring force of the spring means 57a, and the force of the latter spring means acting downwardly on the piston 71a would be balanced by the upwardly-acting fluid pressure force applied to the latter. Should the load decrease, the impeller pressure would increase, causing establishment of communication of the passages 40b and 41b to provide for transfer of liquid from the chamber 52c to the chamber 53c; and, with these passages in communication and as the force of the spring means 57a is greater than that of the spring 84, the piston 26b would be moved upwardly to cause the admission valve to move in a closing direction. Such upward movement of the piston 26b would also cause upward movement of the plug 80a and the piston 71a would move upwardly at a rate depending upon inflow from the constant flow valve 56b, the parts finally coming to rest with restriction of the admission valve suitable for the reduced load and with the various forces acting on the piston valve 27b and on the pistons 26b and 71a in balance. If the load should increase, the piston valve 27b would move upwardly, placing the space 74a in communication with the port 42b, whereby liquid may flow rapidly from the chamber 52d to the chamber 52c to move the operating piston 26b downwardly to open the admission valve wider, the flow of liquid for this purpose depending upon the relatively greater force of the spring means 57a as compared to that of the spring 84. While this operation involves the piston 71a moving downwardly relatively to the upper piston 26b, as the chamber 52d is continuously supplied with liquid by the constant flow valve, at 56b, it will be restored to correct relative position. The pistons 26b and 71a continue to move with opening of the admis-

sion valve until the latter is opened sufficiently for the increase in load and equilibrium of the various forces acting on the piston valve 21b and on the pistons 26b and 71a are restored. Movement of the operating piston transmitted by the follow-up linkage changes the spring force acting on the pilot valve until such force is in balance with the impeller pressure force acting thereon and with the pilot valve in its neutral or normal position. Also, liquid is supplied from the constant flow valve, at 56b, until the lower piston 71a is restored to its normal position relatively to the upper piston 26b, movement of the lower piston ceasing with forces acting thereon in balance and with inflow of liquid to the chamber 52d equal to outflow therefrom. In this connection, it will be noted that the accumulator capacity of the chamber 52d is limited by the plug 80a cooperating with the opening 79a of the piston 71a, the piston moving upwardly until discharge through the opening 79a is equal to that of supply through the constant flow valve 56b.

From the foregoing, it will be apparent that there is provided a servo-motor whose operating piston is moved by liquid furnished from the impeller without impairing the efficacy of the latter to provide speed-responsive or controlling pressure on the pilot valve.

While the invention has been shown in several forms, it will be obvious to those skilled in the art that it is not so limited, but is susceptible of various other changes and modifications without departing from the spirit thereof, and it is desired, therefore, that only such limitations shall be placed thereupon as are specifically set forth in the appended claims.

What is claimed is:

1. In a hydraulic governing system for a prime mover having a controlling element, means providing fluid under pressure varying as a function of the prime mover speed and including a centrifugal impeller driven by the prime mover, hydraulic operating mechanism for the controlling element, means responsive to pressure provided by the impeller for controlling said mechanism, and means including a constant-flow device for supplying fluid from the impeller for motivation of the hydraulic operating mechanism.

2. The combination with a prime mover having an admission valve, of a motor device including an operating movable member connected to the admission valve and pressure-responsive means for controlling the application of inelastic motive fluid to the operating member to secure movement thereof, means operated by the prime mover to provide inelastic fluid under regulating pressure varying as a function of the speed of the prime mover, means for applying fluid under regulating pressure to the pressure-responsive means, and means including a constant flow device utilizing fluid under regulating pressure to provide motivating fluid for the operating member of the motor device.

3. The combination with a prime mover having an admission valve, of a servo-motor including an operating member connected to the admission valve and a pressure-responsive pilot valve controlling the application of inelastic motive fluid to the operating member, an impeller driven by the prime mover and providing inelastic fluid under regulating pressure varying as a function of the speed of the latter, means for applying fluid under regulating pressure to the pressure-responsive pilot valve, and means including a

constant-flow device utilizing fluid delivered by the impeller under regulating pressure to provide motive fluid for the operating member of the servo-motor.

4. The combination with a prime mover having an admission valve, of a servo-motor including an operating member connected to the admission valve and a pressure-responsive pilot valve controlling the application of inelastic motive fluid to the operating member, an impeller driven by the prime mover and providing inelastic fluid under regulating pressure varying as a function of the speed of the latter, means for applying fluid under regulating pressure to the pressure-responsive pilot valve, means including a constant-flow device utilizing fluid under regulating pressure to provide motive fluid for the operating member of the servo-motor, and means utilizing fluid exhausted from the servo-motor to improve the suction lift of the impeller.

5. In hydraulic governing apparatus, an impeller including a runner and a casing, an operating cylinder, an operating piston in the cylinder, means providing motive liquid for the operating cylinder including a conduit connected to the impeller casing, means providing for constant flow through the conduit from the impeller, means for securing operation of the operating piston in the operating cylinder and including a pressure-responsive pilot valve controlling the application of motive liquid to the latter, and means including a conduit connected to the impeller casing for applying impeller pressure to the pressure-responsive pilot valve.

6. In hydraulic governing apparatus, an impeller for developing oil under pressure and including a runner and a casing, an operating cylinder, an operating piston in the cylinder, means providing motive oil for the operating cylinder including a first conduit connected to the impeller casing, means providing for constant flow through the conduit from the impeller, means for securing operation of the operating piston in the operating cylinder and including a pressure-responsive pilot valve controlling the application of motive oil to the latter, means including a second conduit connected to the impeller casing for applying oil under impeller pressure to the pressure-responsive pilot valve, a third conduit for oil discharging from the servo-motor, a constant flow valve in the third conduit, and means including a relief valve for maintaining a substantially constant pressure ahead of the constant flow valve.

7. In hydraulic governing apparatus, an impeller including a runner and a casing, said casing having an eye aligned axially with the runner, a suction conduit communicating with the eye, an operating cylinder, an operating piston in the cylinder, means providing motive liquid for the operating cylinder including a conduit connected to the impeller casing, means providing for constant flow from the impeller through the conduit, means for securing operation of the operating piston in the operating cylinder and including a pressure-responsive pilot valve controlling application of motive liquid to the latter, means including a conduit connected to the impeller casing for applying impeller pressure to the pressure-responsive pilot valve, means including a conduit for liquid exhausted from the operating cylinder, said last-named conduit comprising first and second branches, a valve in the first branch for maintaining a constant pressure ahead thereof and providing for flow there-

through of liquid in excess of that required for the pressure, said first branch having its discharge end communicating with the suction conduit and aligned with the impeller eye, and means providing for constant flow through the second branch.

8. In hydraulic governing apparatus, an impeller including a runner and a casing providing a pressure space, an operating cylinder, an operating piston in the cylinder, a first conduit for supplying liquid from the impeller pressure space to the space of said operating cylinder at one side of the operating piston, a constant flow valve in said conduit, spring means exerting force on the other side of the operating piston, a pilot valve for controlling the discharge of liquid from the space at the first side of the operating piston, means for controlling the pilot valve including a pressure-responsive device, and a second conduit connecting the impeller pressure space with the pressure-responsive device.

9. In hydraulic governing apparatus, an impeller including a runner and a casing providing pressure and suction spaces, a suction conduit for the suction space, an operating cylinder, an operating piston in the cylinder, a second conduit for supplying liquid from the impeller pressure space to the space of said operating cylinder at one side of the operating piston, a constant flow valve in said conduit, spring means exerting force on the other side of the operating piston, a pilot valve for controlling the flow of liquid from the space at the first side of the operating piston to the space at the other side thereof, means for controlling the pilot valve including a pressure-responsive device, a third conduit connecting the impeller pressure space with the pressure-responsive device, and a drainage conduit communicating with the space of the operating cylinder at said other side of the operating piston and having its discharge end communicating with the suction conduit and directed toward the suction space of the impeller in order to improve the suction lift of the latter.

10. In hydraulic governing apparatus, an impeller including a runner and a casing providing a pressure space, an operating cylinder, an operating piston in the cylinder, a first conduit for supplying liquid from the impeller pressure space to the space of said operating cylinder at one side of the operating piston, a constant flow valve in said conduit, spring means exerting force on the other side of the operating piston, a pilot valve for controlling the flow of liquid from the space at the first side of the operating piston to the space at said other side thereof, means for controlling the pilot valve including a pressure-responsive device, a second conduit connecting the impeller pressure space with the pressure-responsive device, a drainage conduit communicating with the space of the operating cylinder at said other side of the operating piston, a constant flow valve in the drainage conduit, and means including a relief valve for maintaining a substantially constant pressure in the drainage conduit ahead of the constant flow valve.

11. In hydraulic apparatus for controlling the position of a prime mover motive fluid admission valve, means providing a drain space; means including an operating piston defining an expandable and contractible chamber; spring means exerting its force on the operating piston in a direction to contract said chamber; means providing a pilot valve chamber and passages con-

nnecting the latter with said first chamber and with said drain space; a pilot valve movable in said pilot valve chamber to control communication of said passages; means including a pressure-responsive device for moving the pilot valve; a device for producing pressure of liquid varying as a function of speed and having a pressure space; means including a first conduit for connecting said pressure space with said contractible and expandable chamber; a constant-flow valve in said first conduit; and a second conduit for connecting said pressure space with said pressure-responsive device.

12. In hydraulic apparatus for controlling the position of a prime mover fluid admission valve; means including a first conduit providing a drain space; means including an operating piston providing a first expandable and contractible space separated by the piston from a portion of the drain space; means including a second piston providing a second expandable and contractible space separated by the second piston from another portion of the drain space; spring means acting on the first and second pistons to contract said first and second spaces; means providing a piston valve bore and first, second and third passages connecting the latter with the drain space, the first expandable and contractible space, and the second expandable and contractible space, respectively; a piston valve in said bore and movable to place said second passage in communication either with the first passage or with the third passage and to interrupt such communication; said piston valve having a piston face cooperating with the bore to provide a pressure chamber; means for throttling escape of liquid from said second expandable and contractible space to the drain space such that, with expansion of the second space beyond a predetermined point, the resistance to escape is very substantially reduced; a device for producing pressure of liquid varying as a function of speed and having pressure and suction spaces; second and third conduits for connecting said pressure space with said second contractible and expandable space and with said pressure chamber, respectively; a constant-flow valve in the second conduit; a first linkage connecting said first piston with the admission valve; a second linkage connecting the first piston with the piston valve and including a spring so disposed that its force opposes that of liquid pressure applied to the piston valve piston face.

13. The combination with a prime mover having an admission valve, of an operating cylinder, an operating piston in the cylinder and connected to the admission valve, biasing means acting on the operating piston to move the admission valve in a closing direction, an accumulator, means operated by the prime mover to provide liquid under regulating pressure varying as a function of the speed of the latter, a conduit for delivering liquid from the last-named means to the accumulator, means providing for constant flow through the conduit, means providing a pilot valve bore, a first passage connecting the pilot valve bore to the operating cylinder to supply liquid to the latter to act on the operating piston against the force of the biasing means to move the admission valve in an opening direction, a second passage connected to the bore and providing a part of the drainage space, a third passage connecting the accumulator and the bore, a pilot valve movable in the bore to connect said first passage either with the

second passage or with the third passage, means including pressure-responsive means for moving the pilot valve, and a conduit for supplying liquid under regulating pressure from said regulating pressure developing means to the pressure-responsive means.

14. The combination with a prime mover having an admission valve, of an operating cylinder, an operating piston in the cylinder and connected to the admission valve, biasing means acting on the operating piston to move the admission valve in a closing direction, an accumulator, means operated by the prime mover to provide liquid under regulating pressure varying as a function of the speed of the latter, a conduit for delivering liquid from the last-named means to the accumulator, means providing for constant flow through the conduit, means providing a pilot valve bore, a first passage connecting the pilot valve bore to the operating cylinder to supply fluid to the latter to act on the operating piston against the force of the biasing means to move the admission valve in an opening direction, a second passage connected to the bore and providing a part of the drainage space, a third passage connecting the accumulator and the bore, a pilot valve movable in the bore to connect said first passage either with the second passage or with the third passage, pressure-responsive means for the pilot valve comprised by a piston face formed on the latter and a portion of the bore, a conduit for supplying liquid under regulating pressure from said regulating pressure-developing means to the pressure-responsive means, means providing for escape of liquid from the accumulator so that liquid may accumulate therein to a predetermined volumetric extent, and follow-up means connecting the operating piston and the pilot valve.

15. The combination with a prime mover having an admission valve; of an operating cylinder; an operating piston in the cylinder and connected to the admission valve; biasing means exerting force on the operating piston to move the admission valve in a closing direction; said operating piston separating the interior of the operating cylinder into a liquid pressure space and a drain space portion with the liquid pressure space so arranged that, with the admission of liquid under pressure thereto, the force thereof acts on the operating piston to move the latter against the force of the biasing means to move the admission valve in an opening direction; an accumulator cylinder; an accumulator piston in the accumulator cylinder and cooperating with the latter to provide an accumulator liquid pressure space; biasing means acting on the accumulator piston to contract said accumulator liquid pressure space; an impeller operated by the prime mover to provide liquid under pressure varying as a function of the speed of the latter, said impeller including a casing cooperating with a runner to provide a liquid pressure space; a conduit for delivering liquid from the impeller pressure space to the accumulator pressure space; a constant-flow valve in said conduit; means providing a pilot valve bore; a first passage connecting the pilot valve bore to the operating cylinder pressure space; a second passage connecting the bore and the drain space portion of the operating cylinder; a third passage connecting the bore and the accumulator pressure space; a pilot valve movable in the bore to connect said first passage either with the second passage or with the third passage; pressure-

responsive means for the pilot valve comprised by a piston face formed on the latter and a portion of the bore; a conduit for supplying liquid from the impeller pressure space to the pressure-responsive means; means providing for escape of liquid from the accumulator pressure space so that a predetermined volume of liquid may accumulate in the latter; and follow-up means including a spring connecting the operating piston and the pilot valve with the spring so arranged that its force opposes the force of liquid pressure exerted on the pilot valve piston face.

16. In hydraulic apparatus for controlling the position of a prime mover motive fluid admission valve, means providing a drain space; means including an operating piston defining an expandable and contractible chamber; spring means exerting its force on the operating piston in a direction to contract said chamber; means providing a pilot valve bore and passages connecting the bore with said chamber and with said drain space; a pilot valve movable in said bore to control communication of said passages; said pilot valve having a piston face cooperating with said bore to provide a pressure chamber; a device for producing pressure of liquid varying as a function of speed and having a pressure space; means including a first conduit for connecting said pressure space with said contractible and expandable chamber; a constant flow valve in said first conduit; a second conduit for connecting said pressure space with said pressure chamber; a first linkage connecting the operating piston and the admission valve; and a second linkage connecting the operating piston and the pilot valve and including a spring so disposed that its force opposes that of liquid pressure applied to the pilot valve piston face.

17. In hydraulic apparatus for controlling the position of a prime mover motive fluid admission valve, means including a first conduit providing a drain space; means including an operating piston defining an expandable and contractible chamber; spring means exerting its force on the operating piston in a direction to contract said chamber; means providing a pilot valve bore and passages connecting the latter with said chamber and with said drain space; a pilot valve movable in said bore to control communication of said passages; said pilot valve having a piston face cooperating with said bore to provide a pressure chamber; a device for producing pressure of liquid varying as a function of speed and including an impeller and a casing therefor; said casing defining suction and pressure spaces and having an eye axially aligned with the impeller and opening into the suction space; means including a second conduit for connecting said pressure space with said contractible and expandable chamber; a constant flow valve in said second conduit; a third conduit for connecting said pressure space with said pressure chamber; a suction conduit connected to the eye of the impeller casing; said first conduit having its discharge end opening into the suction conduit and directed axially toward the eye of the impeller casing so as to assist the suction lift of the impeller; a first linkage connecting the operating piston and the admission valve; and a second linkage connecting the operating piston and the pilot valve and including a spring so disposed that its force opposes that of liquid pressure applied to the pilot valve piston face.

18. In hydraulic apparatus for controlling the position of a prime mover motive fluid admission valve, means including a first conduit providing

a drain space; means including an operating piston defining an expandible and contractible chamber; spring means exerting its force on the operating piston in a direction to contract said chamber; means providing a pilot valve bore and passages connecting the bore with said chamber and with said drain space; a pilot valve movable in said bore to control communication of said passages; said pilot valve having a piston face cooperating with said bore to provide a pressure chamber; a device for producing pressure of liquid varying as a function of speed and having a pressure space; means including a second conduit for connecting said pressure space with said contractible and expandible chamber; a constant

10 15

flow valve in said second conduit; a third conduit for connecting said pressure space with said pressure chamber; a first linkage connecting the operating piston and the admission valve; a second linkage connecting the operating piston and the pilot valve and including a spring so disposed that its force opposes that of liquid pressure applied to the pilot valve piston face; a constant flow valve in said first conduit; and means including a relief valve for maintaining a substantially constant pressure ahead of the constant flow valve and providing for flow therethrough of liquid in excess of that required for the pressure.

HENRY F. SCHMIDT.
